AUTOMATIC THREE-WAY VALVE CONTROL
FOR STEAM HEATING SYSTEMS

Ferdinand N. Borsett, Bronx, N. Y.

Application November 27, 1940, Serial No. 367,366

8 Claims. (Cl. 137—103)

This invention relates to new and useful improvements in an automatic three-way valve control for steam heating systems.

The invention proposes a tank for location just above the water line of the boiler of a furnace, and a novel arrangement including three valves for controlling the passage of the supply of water of condensation from the steam heating system to said tank, and from the tank to the water supply of the boiler of the furnace. The invention is particularly intended for those installations having radiators below the water level of the furnace, in which water of condensation may readily accumulate.

It is proposed that the system be so operated that steam pressure is depended upon to force the water of condensation to the top of said tank, and it is proposed to so operate the three valves that when the water which is blown into the tank reaches a certain predetermined level, the valves are automatically worked to cause the accumulated water to discharge into the water supply of the boiler of the furnace.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a side elevational view of a furnace and steam heating system equipped with a device constructed in accordance with this invention.

Fig. 2 is a vertical sectional view of the tank and the associated mechanism used in this invention.

Fig. 3 is a fragmentary vertical sectional view taken on the line 3—3 of Fig. 2.

Fig. 4 is a sectional view of the air valve used in the invention.

Fig. 5 is a sectional view of one of the steam valves used in the invention.

Fig. 6 is a sectional view similar to Fig. 2 but illustrating a modified construction.

Fig. 7 is a fragmentary elevational view looking in the direction of the line 7—7 of Fig. 6.

Fig. 8 is a fragmentary enlarged horizontal sectional view taken on the line 8—8 of Fig. 7.

The automatic three-way valve system for a steam heat system, in accordance with this invention, includes a tank 10 for location above the water level of a furnace 11 of the system.

A pipe line 12 connects with the top portion of the tank 10 and is adapted to convey water of

condensation from a radiator 13 located beneath the water level line of the boiler of the furnace 11. This radiator 13 is supplied with steam from a live steam line 14 of the boiler of the furnace 11. The pipe line 12 connects with one side of a T-shaped connection 15 mounted on the top of the tank 10.

An air valve 16 for the steam heating system connects with the top of the tank 12 and is controlled with a normally open first master valve 17. More specifically, the air valve 16 is the conventional air valve generally found on radiators, which permits air from the radiator to escape until the radiator becomes hot and then automatically closes to prevent the escape of steam. This air valve 16 is in a pipe line 18 which connects with the top of the T-shaped fitting 15. The first master valve 17 is interposed between the air valve 16 and the tank 10 and is in the pipe line 18, and operates to shut off passage through the line 18, or permits passage through this line.

A steam supply line 20 from the main steam line 14 connects with the top of the tank 10 and is controlled with a normally closed second master valve 21. More specifically, the pipe line 20 connects with one side of the T-fitting 15. The valve 21 is arranged in series in the line 20. The valve 21 controls passage of steam from the supply 14 to the tank 10.

A water discharge 22 from the bottom of the tank 10 is arranged to discharge water directly above the water level of the boiler of the furnace 11 to augment the water supply. This water discharge 22 is controlled with a normally closed third master valve 24. The valves 17, 21 and 24 are preferably superimposed, so that they may be conveniently controlled with an automatic mechanism hereinafter more fully described.

A detail of the valve 17 is shown in Fig. 4. It comprises a valve body 17^a and a valve proper 17^b which is turnable and controlled by a turnable lever 25. As illustrated in Fig. 4 the valve 17 is open. The lever 25 may be turned through a certain angular distance to close the valve. Fig. 5 shows a detail of the valve 21. This valve comprises a valve body 21^a and a turnable valve proper 21^b. This valve proper 21^b is connected with a lever 26 which may be turned to open this valve. The valve 24 is substantially of identical construction to the valve 21. It is provided with a lever 27 which may be turned to open this valve.

A float 30 is located within the tank 10 and is associated with means for closing the first master

valve 17 and opening the second and third master valves 21 and 24, respectively, when the float rises and resetting these valves to their original positions when the float falls. The float 30 is mounted on an arm 31 fixedly secured on a shaft 32. The shaft 32 extends out from one side of the tank 10. A suitable packing gland 33 surrounds the shaft 32 forming a water tight joint.

A segmental gear 34 is mounted on the extended end of the shaft 32 and meshes with a gear 35 on a stud shaft 36 which is turnably supported on the side of the tank 10. This stud shaft 36 has a radial arm 37 upon which a weight 38 is adjustably mounted. A set screw 39 threadedly engages through the weight 38 and abuts the radial arm 37 by which the weight may be secured in various positions along the length of the arm 37. The arm 37 is limited in its pivotal motion from the position illustrated in Fig. 3 which is located by a stationary pin 40 projecting from the side of the tank 10, to a position limited by a stationary pin 41 also projecting from the side of the tank 10.

When the float 30 is in its lower position, as shown in Figs. 2 and 3, the arm 37 rests against the pin 40. When the float rises, the arm 37 will pivot to a position in which it rests against the pin 41. The shaft 36 is provided with a radial arm 43 having a slot 44 which is engaged by a pin 45 mounted on a rod 46. The rod 46 is vertically slidably mounted through bearings 47 and 48 mounted on the side of the tank 10. The lever 25 which controls the valve 17 is formed with a slot 49 engaged by a pin 50 mounted on the rod 46. The lever 26 which controls the valve 21 is provided with a slot 51 engaged by a pin 52 also mounted on the rod 46. The lever 27 which controls the valve 24 is also formed with a slot 53 engaged by a pin 54 mounted on the rod 46.

The operation of the device is as follows:

Normally, steam from the boiler of the furnace 11 passes through the steam feed pipe 14 to the radiator 13 and continues through the pipe 12 to the top portion of the tank 10 and hence along the pipe 18 to the air valve 16 which is closed due to the temperature of the steam. When the water of condensation accumulates in the radiator 13 the passage of steam through the radiator soon becomes blocked. The temperature then falls in the line 18 and the air valve 16 opens. The steam pressure from the feed 14 may now blow the water from the radiator 13 through the pipe 12 to the T-fitting 15.

From the T-fitting 15 the water of condensation will fall into and accumulate in the tank 10. When the water level reaches a certain height the float 30 will start moving upwards. This motion is communicated indirectly to the shaft 36. When the shaft 36 turns the arm 37 will turn correspondingly and so will the arm 43. The arm 43 functions to move the rod 46. When the float reaches a predetermined height the weight 38 passes its dead center and the rod 37 will now rest against the pin 41. At this time the rod 46 has moved a sufficient distance so that the levers 25, 26 and 27 have been moved sufficiently to close the valve 17 and open the valves 21 and 24.

When the valve 21 opens live steam enters the tank 10. This live steam cannot pass out of the air valve 16 because the first master valve 17 has been closed. Since the valve 24 opens simultaneously with the valve 21 the water within the tank 10 is now free to flow into the boiler of the furnace 11. In view of the fact that the steam pressure of the boiler is acting on the top of the

water in the tank 10 it will flow through the line 22 into the water supply of the boiler. When this happens the water level falls, and the float 30 moves downwards following the water level. This causes the arm 37 and the rod 46 to move correspondingly. Soon the arm 37 passes its dead center and starts returning to its initial position as shown in Fig. 3. Soon the rod 46 has moved sufficiently to reopen the valve 17 and reclose the valves 21 and 24. The parts are now in their initial positions.

In Figs. 6 and 7 a modified form of the invention has been disclosed which distinguishes from the prior form in the provision of means for delaying the resetting of the master valves until the float falls a predetermined amount. According to this form of the invention there is an auxiliary float 58 located within the tank 10 and provided with a supporting rod 59 having an elongated slot 60. This rod 59 is hooked upon the arm 31' of the float 30. This arm 31' is provided with a pair of lugs 61 arranged on opposite sides of the rod 59 so as to limit motion of the rod to the vertical direction only. The weight 38 is so set upon the arm 37 that the float 30, acting alone, is not capable of moving the weight past its dead center when the arm 37 rests against the pin 41.

In other respects this form of the invention is identical to the previous form and like parts are indicated by like reference numerals.

The operation of this form of the invention is as follows:

As the water condensation enters the tank 10 the float 58 will move upwards until the float 58 strikes against the arm 31'. Then the rising water level in the tank 10 will lift the floats 30 and 58 simultaneously. This simultaneous action will cause turning of the shaft 32 which operates the various mechanism in the identical fashion as previously described. The arm 37 will soon pass its dead center and engage the pin 41. At this time, the valve 17 will be closed and the valves 21 and 24 will be opened and the water in the tank 10 will be flowing into the boiler of the furnace 11.

As the water level falls the float 58 will move downwards, but the float 30 will remain in its raised position since it is incapable of pivoting the arm 37 past its dead center. The water level keeps falling until the float 58 reaches a position in which the rod 59 hinges on the arm 31'. Then the sum of the weights of the floats 30 and 58 will be sufficient to pivot the arm 37 past its dead center. This causes turning of the shaft 32 and the device operates to reopen the valve 17 and close the valves 21 and 24 in a manner identical to that previously described.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described having a tank and pipe lines carrying water to and from said tank and controlled by valves connected to a slidably mounted rod, means for moving said rod to open or close said valves in unison, comprising a shaft extended through one wall of said tank, a float mounted on the inner end of

said shaft to move up and down as the level of said water changes to rotate said shaft, a segmental gear mounted on the outer end of said shaft, a stud shaft rotatively mounted on the outside of said tank, a gear fixedly mounted on said stud shaft and meshing with said segmental gear to rotate said stud shaft, and means connecting said stud shaft with said rod to cause said rod to move therewith.

2. In a device of the class described having a tank and pipe lines carrying water to and from said tank and controlled by valves connected to a slidably mounted rod, means for moving said rod to open or close said valves in unison, comprising a shaft extended through one wall of said tank, a float mounted on the inner end of said shaft to move up and down as the level of said water changes to rotate said shaft, a segmental gear mounted on the outer end of said shaft, a stud shaft rotatively mounted on the outside of said tank, a gear fixedly mounted on said stud shaft and meshing with said segmental gear to rotate said stud shaft, and means connecting said stud shaft with said rod to cause said rod to move therewith, comprising an arm having one end mounted on said stud shaft and its free end extended radially and overlying a portion of said rod, and a pin extending from said rod and engaging an elongated slot formed in the free end of said arm.

3. In a device of the class described having a tank and pipe lines carrying water to and from said tank and controlled by valves connected to a slidably mounted rod, means for moving said rod to open or close said valves in unison, comprising a shaft extended through one wall of said tank, a float mounted on the inner end of said shaft to move up and down as the level of said water changes to rotate said shaft, a segmental gear mounted on the outer end of said shaft, a stud shaft rotatively mounted on the outside of said tank, a gear fixedly mounted on said stud shaft and meshing with said segmental gear to rotate said stud shaft, and means connecting said stud shaft with said rod to cause said rod to move therewith, and means for limiting movement of said float to positions in which said valves are opened or closed.

4. In a device of the class described having a tank and pipe lines carrying water to and from said tank and controlled by valves connected to a slidably mounted rod, means for moving said rod to open or close said valves in unison, comprising a shaft extended through one wall of said tank, a float mounted on the inner end of said shaft to move up and down as the level of said water changes to rotate said shaft, a segmental gear mounted on the outer end of said shaft, a stud shaft rotatively mounted on the outside of said tank, a gear fixedly mounted on said stud shaft and meshing with said segmental gear to rotate said stud shaft, and means connecting said stud shaft with said rod to cause said rod to move therewith, and means for limiting movement of said float to positions in which said valves are opened or closed, comprising a rod extending radially from said stud shaft, a pin mounted on said tank and against which said rod is adapted to rest in one position of said float, and a second pin mounted on said tank and spaced from said first pin and against which said rod is adapted to rest in the other position of said float.

5. In a device of the class described having a tank and pipe lines carrying water to and from

said tank and controlled by valves connected to a slidably mounted rod, means for moving said rod to open or close said valves in unison, comprising a shaft extended through one wall of

5 said tank, a float mounted on the inner end of said shaft to move up and down as the level of said water changes to rotate said shaft, a segmental gear mounted on the outer end of said shaft, a stud shaft rotatively mounted on the outside of said tank, a gear fixedly mounted on said stud shaft and meshing with said segmental gear to rotate said stud shaft, and means connecting said stud shaft with said rod to cause said rod to move therewith, said float being mounted upon the free end of a radial arm projecting from the inner end of said shaft, and an additional float mounted on said arm for supplementing the lifting and lowering force of said first float.

10 6. In a device of the class described having a tank and pipe lines carrying water to and from said tank and controlled by valves connected to a slidably mounted rod, means for moving said rod to open or close said valves in unison, comprising a shaft extended through one wall of

15 said tank, a float mounted on the inner end of said shaft to move up and down as the level of said water changes to rotate said shaft, a segmental gear mounted on the outer end of said

20 shaft, a stud shaft rotatively mounted on the outside of said tank, a gear fixedly mounted on said stud shaft and meshing with said segmental gear to rotate said stud shaft, and means connecting said stud shaft with said rod to cause

25 said rod to move therewith, said float being mounted upon the free end of a radial arm projecting from the inner end of said shaft, and an additional float mounted on said arm for supplementing the lifting and lowering force of said first float.

30 7. In a device of the class described having a tank and pipe lines carrying water to and from said tank and controlled by valves connected to a slidably mounted rod, means for moving said rod to open or close said valves in unison, comprising a shaft extended through one wall of

35 said tank, a float mounted on the inner end of said shaft to move up and down as the level of said water changes to rotate said shaft, a segmental gear mounted on the outer end of said

40 shaft, a stud shaft rotatively mounted on the outside of said tank, a gear fixedly mounted on said stud shaft and meshing with said segmental gear to rotate said stud shaft, and means connecting said stud shaft with said rod to cause

45 said rod to move therewith, said float being mounted upon the free end of a radial arm projecting from the inner end of said shaft, and an additional float mounted on said arm for supplementing the lifting and lowering force of said first float.

50 8. In a device of the class described having a tank and pipe lines carrying water to and from said tank and controlled by valves connected to a slidably mounted rod, means for moving said rod to open or close said valves in unison, comprising a shaft extended through one wall of

55 said tank, a float mounted on the inner end of said shaft to move up and down as the level of said water changes to rotate said shaft, a segmental gear mounted on the outer end of said

60 shaft, a stud shaft rotatively mounted on the outside of said tank, a gear fixedly mounted on said stud shaft and meshing with said segmental gear to rotate said stud shaft, and means connecting said stud shaft with said rod to cause

65 said rod to move therewith, said float being mounted upon the free end of a radial arm projecting from the inner end of said shaft, and an additional float mounted on said arm for supplementing the lifting and lowering force of said first float.

70 9. In a device of the class described having a tank and pipe lines carrying water to and from

8. In a device of the class described having a tank and pipe lines carrying water to and from said tank and controlled by valves connected to a slidably mounted rod, means for moving said rod to open or close said valves in unison, comprising a shaft extended through one wall of said tank, a float mounted on the inner end of said shaft to move up and down as the level of said water changes to rotate said shaft, a segmental gear mounted on the outer end of said shaft, a stud shaft rotatively mounted on the outside of said tank, a gear fixedly mounted on said stud shaft and meshing with said segmental gear to rotate said stud shaft, and means connecting said stud shaft with said rod to cause said rod to move therewith, said float being mounted upon

10 the free end of a radial arm projecting from the inner end of said shaft, and an additional float mounted on said arm for supplementing the lifting and lowering force of said first float, said 15 mounting of said additional float, comprising a rod extended from said additional float and having an elongated slot through which said arm slidably extends requiring said water to rise or fall a certain degree before the ends of said slot strike said arm to bring the weight of said additional float into play, and means on said arm limiting movement of said float and rod to the vertical, comprising lugs formed on said arm on opposite sides of said rod.

FERDINAND N. BORSETT.
